Electric & Manufacturing Company, East Pitts-
burgh, Pa., a corporation of Pennsylvania

Application March 4, 1939, Serial No. 259,863

2 Claims. (Cl. 219—37)

Our invention relates to heating units, and more particularly to the construction of range surface units.

Prior art heating units or range surface units have in some cases been formed from elongated metallic-sheathed tubes. However, in all known cases, such tubes have been welded, either together or to a suitable support. The welding of such tubes requires great patience and hand work so that the metallic sheath will not be ruptured, due to the intense welding temperatures required. The cost of such units is accordingly, relatively high. If a satisfactory unit of this character could be produced without the need of welding, the cost thereof would be greatly reduced.

It is, therefore, an object of our invention to provide a range surface unit constructed from an elongated metallic sheathed heating element which is bound together into a unitary structure without the use of welding, or the like.

A further object of our invention is to provide range surface units from elongated heating elements having interlocking complementary sides.

A still further object of our invention is to provide an efficient, inexpensive, range surface unit which will be easy to form and which has additional removable means for retaining the structure in its predetermined configuration.

Other objects of our invention will either be pointed out specifically in the course of the following description embodying our invention, or will be apparent from such description.

In the accompanying drawing:

Figure 1 is a top plan view of a device embodying our invention;

Fig. 2 is a sectional view taken along the line II—II of Fig. 1;

Fig. 3 is an enlarged fragmentary view similar to Fig. 2; and

Fig. 4 is a view similar to Fig. 2 illustrating a modified form of our invention.

Referring to the accompanying drawing, we show a range surface unit structure 10 comprising an upper heating unit 12, a lower insulating block 14 and a supporting structure 16. The heating unit 12 includes an elongated metallic sheathed tubular heating element 18, a central disk 20, preferably of metallic material, and a suitable binding member 22 for retaining the unit 12 in a predetermined configuration.

The heating element 18 comprises an elongated metallic sheath or casing 24, a helically coiled resistor 26 and suitable insulating material 28.

5 positioned within the tubular casing 24 so as to insulate the resistor therefrom. The cross-section of the casing 24 is, in this instance, substantially rectangular in shape. However, vertical sides of the casing 24 have irregular portions 30 and 32 located therein. The irregular portions 30 and 32 are complementary to each other such as a groove 30 and a head 32, so that the cooperating portions of the sheath will be permitted to contiguously engage with each other, substantially as hereinafter described.

The intruding portion or groove 30 extends inwardly into the casting 24 and is located along one side thereof, in this instance, substantially semi-cylindrical in shape. In addition, the intruding portion 30 extends along the full length of the casting 24. However, it is to be understood that such inwardly extending portion 30 may be of any desired cross-section and may be of any suitable length.

20 The protruding portion or head 32 is located on the diametrically opposite side of the sheath 24. The protruding portion 32 is substantially the reverse configuration of the inwardly extending portion 30. In other words, the portion 32 extends outwardly from the side walls of the casting 24, in this instance, in a semi-cylindrical manner, being substantially the same length as the inwardly extending portion 30.

25 The metallic sheath 24 may be formed in any desirable shape and in any suitable manner as by drawing through suitable dies or by rolling, swaging, etc. However, it is to be understood that the irregularly shaped portions 30 and 32 must be formed therein so as to complementarily cooperate with each other, substantially as hereinafter described.

30 The heating unit 12 has, in this instance, a centrally located irregularly-shaped disc 20. The disc 20 has a height substantially equal to the height of the metallic sheath 24. In addition, the disc 20 has a groove 21 cut therein substantially the same shape as the inwardly protruding portion 30 of the metallic sheath 24. The groove 21 is thus complementary to the protruding portion 32. The inwardly extending groove 21 thus permits the protruding portion 32 of the sheath to cooperate therewith.

35 The disc 20 in this instance is illustrated as being a solid unitary metallic member. However, it is to be understood that such disc 20 may be formed of a plurality of members, and may include, if desired, a removable simmer heater.

40 The binding member or ring 22 is formed from

45

50

55

a suitable metallic material which has a cross-section substantially the same as the inwardly extending portion 30 of the metallic sheath 24. In other words, the cross-section of the ring 22 will be substantially a semi-circle, see Figs. 2 and 3. It, therefore, follows that the ring 22 may be wound around the outside of the heating unit 12 and positioned within the outside inwardly extending portion 30 of the case 24, for a purpose and in a manner hereinafter described.

When constructing the heating unit 12 embodying our invention, one or more of the elongated metallic sheathed tubular heating elements 18 is positioned along side the disc 20 in such a manner that the protruding portion 32 thereof will complementarily extend into the groove cut 21 within the side of the disc 20. The heating element 18 is then tightly wound around the disc 20 in a spiral manner, so that each succeeding whorl of the element 18 will contiguously engage the preceding whorl. As the heating element is wound in such a spiral manner, the protruding portion 32 of the casing 24 will cooperate with and be complementary to the intruding portion 30 of the preceding whorl. In other words, there will be an interlocking engagement between each two adjacent turns of the heating element.

After the heating element 18 has been completely wound around the disc 20, so as to form a circular unitary structure, the ring 22 is tightly wound around the outside or periphery thereof and positioned within the intruding portion 30 of the outer whorl of such heating unit 18. The free ends of the ring 22 are then rigidly attached together such as by riveting or welding (see 23 in Fig. 1) whereupon the heating unit 12 will be formed into a rigid solid unit. In addition, the ring 22 will retain the heating element in its predetermined fixed configuration. In this manner, a thermally efficient and mechanically rigid heating unit, with a flat top suitable for cooking purposes is provided.

If desired, a suitable bolt 34 may be rigidly attached to the lower portion of disc 20 to attach the heating unit 12 to the supporting pan 16. With such an arrangement being used, the insulating block 14 is positioned within the supporting pan or structure 16 whereupon the heating unit 12 is located thereover with bolt 34 extending through the central portion of insulating block 14 and through the bottom of the pan 16. A suitable nut may be run on the end of the bolt 34 to rigidly attach the heating unit 12 and insulating block 14 to the supporting pan 16, so as to form a complete range surface unit 10. However, it is to be understood that the heating unit 12 may be attached to the supporting structure in any other desired manner.

If desired, a suitable dummy block or tube 36 (see Fig. 4) constituting a spacer member and

having substantially the same configuration as the heating element 18 may be wound parallel with the heating element 18 around the disc 22. The block or tube 36 may be formed of any suitable heat conducting material and may be either solid or hollow, depending upon the amount of mass desired in the heating unit. It is preferred that the block or tube 36 be as light and thin as feasible inasmuch as the unit should have as light a mass as possible. The dummy tube 36 separates the whorl of the heating element 18 and limits the length of such heating element utilized for a given sized surface unit. It, therefore, follows that the dummy block or tube 36 may be of any desired width depending upon the amount of separation desired between each succeeding spirals or whorls of the heating element 18.

By having the side walls of the elongated metallic sheathed tubular element complementarily deformed, it is obvious that, when such heating element is tightly wound around a suitable centrally located disc and retained in such configuration, that the heating unit will be formed into a solid unit or structure.

Various other modifications may be made in the device embodying our invention without departing from the spirit and scope thereof, and we desire, therefore, that only such limitations shall be placed thereon as are imposed by the prior art and the appended claims.

We claim as our invention:

1. An electric heating unit including, in combination, an elongated substantially rectangular sheathed heating element having an elongated bulged portion on one vertical side of the sheath and an elongated grooved portion on the opposite vertical side, said element being wound spirally in a contiguous manner with the two portions complementary on contiguous whorls and the confronting vertical sides in engagement to form a substantially flat surface, and means for retaining said spirally wound element in such predetermined configuration.

2. An electric heating unit including, in combination, an elongated substantially rectangular sheathed heating element having an elongated bulged portion on one vertical side and an elongated grooved portion on the opposite vertical side, a disc having a groove in its vertical peripheral surface, said element being wound spirally in a contiguous manner about such disc with the two portions being complementary on contiguous whorls and with the bulging portion of the first whorl cooperating with the groove in the disc, confronting vertical faces in all cases being in contact, and means for retaining said spirally wound element in such predetermined configuration.

ALFONS BARNSTEINER.
EDWIN H. LOCKWOOD.
